(57) **CLAIM**

The ornamental design for an exercise box, as shown and described.

DESCRIPTION

FIG. 1 is a perspective view of an exercise box design showing my new design.

FIG. 2 is a front view of an exercise box.

FIG. 3 is a rear view of an exercise box.

FIG. 4 is a left side view of an exercise box.

FIG. 5 is a right side view of an exercise box.

FIG. 6 is a top view of an exercise box.

FIG. 7 is a bottom view of an exercise box.

FIG. 8 is a perspective view of an exercise box, shown in a state of use; and,

FIG. 9 is another perspective view of an exercise box, shown in a state of use.

The broken lines in the drawings depict portions of the exercise box that form no part of the claimed design.

1 Claim, 9 Drawing Sheets
